UNITED STATES PATENT OFFICE

OLIVER B. ANDREWS, OF CHATTANOOGA, TENNESSEE

COMPOUND BOX

Application filed September 4, 1929. Serial No. 390,234.

This invention relates to folded boxes, and more particularly to a compound box which is strong and rigid and is adapted for use in shipping heavy articles.

5 The box in particular comprises an inner container of folded box board which is inserted within an outer sleeve formed of relatively stiff waterproof material. The sleeve is closed by separate top and bottom elements 10 which are provided with flanges extending between the inner box and the outer sleeve by means of which the elements are secured.

In accordance with the present invention the flanges on the top and bottom elements 15 are so formed that they may be readily inserted between the inner and outer sections of the box and are frictionally held in place. The entire assembly may then be secured by straps surrounding the outer box.

20 The invention also consists in certain new and original features of construction and combinations of parts hereinafter set forth and claimed.

Although the novel features which are believed to be characteristic of this invention 25 will be particularly pointed out in the claims appended hereto, the invention itself, as to its objects and advantages, the mode of its operation and the manner of its organization 30 may be better understood by referring to the following description taken in connection with the accompanying drawings forming a part thereof, in which

Fig. 1 is a perspective view partly in section showing the assembled box;

Fig. 2 is a section taken on the line 2-2 of Fig. 1;

Fig. 3 is a perspective of the inner box showing the construction thereof;

Fig. 4 is a perspective view of the component parts of the box showing the inner box telescoping within the outer sleeve;

Fig. 5 is a perspective view of the component parts of the box in disassembled relationship;

Fig. 6 is an enlarged detail view of a portion of the blank from which the top and bottom sections are formed; and

Fig. 7 is a section taken on the line 7-7 of Fig. 6.

Like reference characters denote like parts in the several figures of the drawings.

In the following description and in the claims parts will be identified by specific names for convenience, but they are intended to be as generic in their application to similar parts as the art will permit. 55

Referring to the drawings more in detail, the invention is shown as comprising a compound box formed of an inner container 60 (Fig. 3) comprising side members 10 and end members 11 together with side flaps 12 and end flaps 13, which is formed from a blank in any desired manner. The box may be folded as shown in Fig. 3 and secured by suitable 65 means such as tape 14 attached to adjacent surfaces 10 and 11 after which flaps 12 and 13 may be folded inwardly to form a completely closed box as shown in Figs. 4 and 5.

The inner container is preferably formed 70 of corrugated board or other stiff box board and is suitably creased to permit the various surfaces to be folded into their desired positions. Due to the thickness of the board the creases are in the form of a slight roll rather than a sharp bend. This feature is utilized, 75 as will be pointed out hereinafter in distributing stresses to which the box is subjected and avoiding crushing.

The outer sleeve comprises a pair of side 80 members 17 which are provided with in-turned flanges 18. These flanges are secured to end members 19 by suitable means, such as stitches 20. It is to be noted that the corners of the sleeve are reinforced by the double 85 thickness of flanges 18 and end members 19. This is also an important feature in imparting the desired rigidity to the assembled box.

Top member 21 and bottom member 21a 90 are made from a blank of box board which is suitably cut to form flaps 22 and 23 respectively. The top and bottom members are preferably identical, hence only one of these members has been shown in detail.

Referring to Figs. 6 and 7, compound 95 creases 24 are formed in the box board between cover 21 and flaps 22. These creases are so arranged that strip 25 which is included therebetween is bent at an angle intermediate the flaps and the cover member. 100

This is shown in dotted lines in Fig. 7 and in Fig. 2 in which strip 25 is bent at an angle of 45° to cover member 21, and flap 22 is bent at an angle of 90° to said cover member.

5 Edges 26 of flaps 22 are inclined with respect to creases 24 whereby the flaps are formed slightly wedge shaped. When the flaps are bent into upright position the inclined edges 26 form an open notch on the 10 four corners of the top member which permits flaps 22 to be more readily inserted between the inner container and the outer sleeve. It is to be noted that edge 26 is formed on the blank (Fig. 6) as a straight 15 line extending through flaps 22 and strips 25. Both of these elements are accordingly wedge shaped. When strip 25 is bent at an angle of 45°, as shown in Figs. 4 and 5, the adjacent portions of flaps 22 at the corners of the cover 20 member are separated by an appreciable distance which provides clearance at the corners of the box when the flaps are inserted between the inner and outer members. This construction permits flaps 22 to be extended approximately 25 to the corners of the box without binding and interfering with the assembly thereof.

Bottom member 21a and flaps 23 are similarly formed, and it is to be understood that 30 the description above applies equally to that portion of the box.

The outer sleeve and the top and bottom members are preferably formed of a heavy fiber board which has been impregnated on 35 the inside and outside with a waterproofing solution which hardens on drying to produce a particularly hard surface. A solution of silicate of soda has been found suitable for this purpose. This solution penetrates the board to a slight extent and produces a coating which is both rigid and impervious to moisture. The strength of the fiber board so treated is materially increased and a more rigid box is produced.

45 In assembling the above described box the material to be shipped is packed within the inner container after which flaps 12 and 13 are folded to completely close the same. The inner container is then placed within the 50 outer sleeve and the top and bottom members are inserted in their proper place. After this the entire box may be held closed by suitable bands 30 which may be of any strong material, such as thin metal.

55 When a box of this character is subjected to hard usage, as for example, a blow on one corner, the blow is absorbed by the double thickness at the corner of the outer sleeve and is transmitted through the flaps 22 and 23 60 to the inner container where it is distributed over a considerable portion of the adjacent surface. The V-shaped opening between adjacent flaps 22 and 23 prevents the blow from being transmitted directly to the corner 65 of the inner container. The rounded

creases of the inner container also provide a slight clearance between the two elements and help in securing the proper distribution of stresses.

If the blow on the corner of the box is occasioned by allowing the box to fall, the material within the box will exert pressure from the inside which is distributed over a comparatively large area of the outer sleeve in a similar manner. 70

The box is particularly applicable to the shipment of heavy articles and has been used, for example, for cordage in amounts up to 400 lbs. It has been found that boxes of this size were capable of withstanding shocks which would fracture a thin wooden crate which had heretofore been used for the same purpose. Furthermore, the resilience of the box board and the even distribution of the stresses prevent the material from becoming chafed or injured under ordinary conditions of usage. 80

85 While certain novel features of the invention have been shown and described and are pointed out in the annexed claims, it will be understood that various omissions, substitutions and changes in the forms and details of the device illustrated and in its operation may be made by those skilled in the art without departing from the spirit of the 95 invention.

90 What is claimed is:

1. In a folded box, an inner container of folded box board, an outer sleeve completely surrounding said inner container, top and bottom members having flaps secured thereto adapted to be inserted between said inner container and said sleeve, said flaps being wedge shaped whereby notches are provided at the corners of the box to permit a clearance between the inner container and the outer sleeve at those points. 105

2. A strong folded box comprising an inner container having flanges infolded to form a complete closure, an outer sleeve surrounding said inner container, top and bottom members having inturned flaps and intermediate strips between said members and said flaps extending at an angle intermediate to the angle of said flaps with respect to said member, said flaps being inserted between said sleeve and said inner container. 110

3. A strong folded box comprising an inner container having flanges infolded to form a complete closure, an outer sleeve of fiber board comprising side members and end members, top and bottom members having inturned flaps and intermediate strips between said members and said flaps extending at an angle intermediate to the angle of said flaps with respect to said member, said flaps and intermediate strips having inclined edges whereby clearance is provided at the corners, said flaps being inserted between said sleeve and said inner container. 120

4. A strong folded box comprising an inner container having flanges infolded to form a complete closure, the creases about which said flaps are folded comprising a slight roll, an outer sleeve comprising side members and end members, top and bottom members of stiff board having inturned flaps and intermediate strips between said members and said flaps extending at an angle intermediate to the angle of said flaps with respect to said member, said flaps and intermediate strips having inclined edges whereby clearance is provided at the corners, said flaps being inserted between said sleeve and said inner container. 70
5. A strong folded box comprising an inner container of corrugated box board having flanges infolded to form a complete closure, an outer sleeve of stiff fiber board comprising side members having inturned flanges and end members stitched to said flanges at the corners of said sleeve, top and bottom members of stiff fiber board having inturned flaps and intermediate strips between said members and said flaps extending at an angle intermediate to the angle of said flaps with respect to said member, said flaps and intermediate strips having inclined edges whereby clearance is provided at the corners, said flaps being inserted between said sleeve and said inner container. 80
6. A strong folded box comprising an inner container of corrugated box board having flanges infolded to form a complete closure, the creases about which said flaps are folded comprising a slight roll, an outer sleeve of stiff fiber board comprising side members having inturned flanges and end members stitched to said flanges at the corners of said sleeve, top and bottom members of stiff fiber board having inturned flaps and intermediate strips between said members and said flaps extending at an angle intermediate to the angle of said flaps with respect to said member, said flaps and intermediate strips having inclined edges whereby clearance is provided at the corners, said flaps being inserted between said sleeve and said inner container, said sleeve and said top and bottom members being impregnated with a waterproofing solution capable of producing a hard strong surface layer. 85
7. A strong folded box comprising a closed inner container, an outer sleeve of box board surrounding said container, top and bottom members of stiff box board having inturned flaps and intermediate strips between said members and said flaps extending at an angle intermediate to the angle of said flaps with respect to said member, said flaps and intermediate strips having inclined edges whereby clearance is provided at the corners, said flaps being inserted between said sleeve and said inner container, said sleeve and said top and bottom members being impregnated with a solution of silicate of soda. 90
